DESIGN FOR A COMBINED CHAIR, ARMREST, AND VIBRATOR

John Werner, Chicago, and Albert H. Zeigler,
Kenilworth, Ill., assignors to Aciform Corpora-
tion, Chicago, Ill., a corporation of Illinois

Application November 12, 1947, Serial No. 142,479

Term of patent 7 years

(Cl. D15—1)

To all whom it may concern:

Be it known that we, John Werner and Albert H. Zeigler, both citizens of the United States of America, and residents of Chicago and Kenilworth in the county of Cook and State of Illinois respectively, have invented a new, original, and ornamental Design for a Combined Chair, Arm Rest, and Vibrator, of which the following is a specification, reference being had to the accompanying drawing, forming part thereof.

Figure 1 is a perspective view of a combined chair, arm rest, and vibrator, showing our new design.

Fig. 2 is a top plan view thereof.

Fig. 3 is a rear elevational view thereof.

Fig. 4 is a side elevational view thereof with a part of the arm rest shown broken away for convenience of illustration.

The center portion of the back as shown in

Figure 1 is solid and is shaded differently from the side panels in order to show a contrast in color.

We claim:

The ornamental design for a combined chair, arm rest, and vibrator, as shown and described.

JOHN WERNER.

ALBERT H. ZEIGLER.
